CABINET FOR DENTAL AIR SUCTION APPLIANCES

Thomas R. Cox, 91 Delmar Drive, Hamilton, Ontario,
Canada, and Donald G. Coburn, Jerseyville Road E.,
Ancaster, Ontario, Canada

Filed Aug. 1, 1962, Ser. No. 71,134

Term of patent 14 years

(Cl. D24—1)

FIG. 1 is a perspective view of a cabinet for dental air suction appliances showing our new design; the sides not shown are a mirror image of the sides shown.

FIG. 2 is a front elevation thereof.

We claim:

The ornamental design for a cabinet for dental air suction appliances, as shown and described.
